HINGE

Leonard W. Clover, 505 Flagg Ave.,
San Jose, Calif. 95128

Filed July 13, 1966, Ser. No. 3,055

Term of patent 14 years

(Cl. D10—9)

FIG. 1 is a side elevational view of a hinge showing my new design therefor.

FIG. 2 is a barrel end view of the same as seen from the right-hand side of FIG. 1.

FIG. 3 is a side elevational view of the hinge of FIG. 1 showing the opposite side thereof.

FIG. 4 is a wing end view of the hinge as seen from the right-hand side of FIG. 3.

FIG. 5 is a top plan view of the hinge as seen from above in FIG. 3, the bottom plan thereof being identical.

FIG. 6 is an exploded perspective view of the hinge halves separated.

FIG. 7 is a plan view looking upwardly at line 7 in FIG. 6.

FIG. 8 is a plan view looking downwardly at line 8-8 in FIG. 6.

I claim:

The ornamental design for a hinge, as shown and described.
